UNITED STATES PATENT OFFICE.

HARRY T. AUBRY, OF CHICAGO, ILLINOIS.

SHELF-BRACKET.

1,108,543.

Specification of Letters Patent. Patented Aug. 25, 1914.

Application filed November 19, 1913. Serial No. 801,844.

To all whom it may concern:

Be it known that I, HARRY T. AUBRY, a citizen of the United States, residing at Chicago, in the county of Cook and State of Illinois, have invented certain new and useful Improvements in Shelf-Brackets, of which the following is a specification.

The bracket which is the subject-matter of the present application for patent is designed more particularly for supporting shelving, and the object of the invention is to provide a bracket which is adjustable to support the shelf boards in longitudinal alinement or at an angle. This object is attained by means of a bracket embodying certain novel features of construction to be hereinafter described and claimed.

In order that the invention may be better understood, reference is had to the accompanying drawing, in which—

Figure 1 is a perspective view of the bracket. Fig. 2 is a perspective view of one end of the bracket. Fig. 3 is a cross-section on the line 3—3 of Fig. 1, and Fig. 4 is a plan view showing the bracket member set to support the shelf boards in angular position.

Referring specifically to the drawing, the bracket is composed of two pivotally connected members 10 of triangular skeleton form to reduce the weight and cheapen the construction. The members are connected by a hinge pintle 11 which passes through matching knuckles 12 on the adjacent ends 30 of the members. The length of the pintle is greater than the height of the bracket, and its upper end has a head 13 which is for a purpose to be presently described. The lower end of the pintle is threaded to receive a nut 14. The outer end of each bracket member 10, at the top thereof, has an upward projection 15 which is enlarged, laterally, at the top, as indicated at 16, and flattened to form a support for the shelf 40 board 17, said enlargement having perforations 18 at its ends through which pass bolts or other fastening means 19 which secure the shelf board. The bracket is mounted on a post or other support 20, the latter carrying 45

a plate 21 having an outstanding lug 22 provided with a vertical aperture through which the lower end of the pintle 11 is passed. The nut 14 is screwed on the lower end of the pintle, against the bottom of the lug 22.

In use, the shelf boards 17 are placed on the flattened and enlarged top 16 of the projections 15, and secured by the bolts 19, the latter passing through the boards and the perforations 18, and being secured by nuts 23 screwed on said bolts against the bottom 55 of the parts 16. The ends of the boards 17 meet and overlap in line with the pintle 11, and the latter is passed through the overlapping parts, the head 13 fitting down on top of one of the boards. The shelf boards are 60 securely held in place by this fastening, and they may thus be secured in alinement or placed at an angle to each other. In the first-mentioned position, the two bracket members 10 are positioned in alinement, and 65 in the second position, they are swung to extend at an angle conforming to the angle it is desired to give the shelf boards.

I claim:

1. A bracket composed of a pair of members having matching hinge-knuckles, and a pintle passing through said knuckles, the upper end of the pintle rising above the top of the members, said top being shaped to support a shelving through which the upper 70 end of the pintle is adapted to pass.

2. A bracket composed of a pair of members having matching hinge-knuckles, and a pintle passing through said knuckles and projecting from the top and bottom of the 75 members, the top of the members being shaped to support a shelving through which the upper end of the pintle is adapted to pass, and a support for the bracket members having an aperture through which the lower 80 end of the pintle passes.

In testimony whereof I affix my signature in presence of two witnesses.

HARRY T. AUBRY.
